CLAIM

The ornamental design for a deck of playing cards, as shown and described.

DESCRIPTION

FIG. 1 is a face up view of one suit of the deck of playing cards.

FIG. 2 is a face up view of one suit of the deck of playing cards.

FIG. 3 is a face up view of one suit of the deck of playing cards.

FIG. 4 is a face up view of one suit of the deck of playing cards.

FIG. 5 is a face down view of the deck of playing cards.

FIG. 6 is a top view of the deck of playing cards.

FIG. 7 is a bottom view of the deck of playing cards.

FIG. 8 is a right-side view of the deck of playing cards; and, FIG. 9 is a left-side view of the deck of playing cards.

In the drawings, the broken lines depict environmental subject matter only and form no part of the claimed design.
